SHAPER

Earl B. Peterman, Canfield, Ohio

Application September 6, 1941, Serial No. 409,869

1 Claim. (Cl. 144—134)

This invention relates to a fiber wedge cutting device.

The principal object of the invention is the provision of a fiber wedge cutting device adapted to shape or taper the edges of fiber strips commonly used in the rebuilding of armatures of electric motors, and generators.

A further object of the invention is the provision of fiber shaping device adapted to simultaneously bevel the edge of a fiber strip.

A further object of the invention is the provision of a fiber shaping device wherein standard tool stock is used as the actual cutting tool.

A still further object of the invention is a provision of a fiber wedge cutting device wherein a relatively small motor forms a sufficiently strong power source to operate the device due to the unique arrangement of the fiber engaging tools.

The fiber wedge cutting device shown and described herein has been designed to facilitate the formation of insulating fiber wedge members, a great number of which are used in the rebuilding of armatures of electric motors and generators.

As is known in the art, these fiber wedges are necessarily beveled on their edges in order to conform to the structural shape of the positions they occupy in the armatures. Heretofore, it has been necessary to shape the fiber wedges on such means as were commonly available for the work and which means often comprised grinding stones, planing devices, and similar machines not adapted for the accurate work necessary.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

Figure 1 is a top plan view of the fiber wedge cutting device.

Figure 2 is a side elevation with parts in cross-section showing the fiber wedge cutting device.

By referring to the drawing and to Figure 2 in particular, it will be seen that a table 10 is provided with a cylindrical structure depending therefrom and has rotatably positioned centrally therein a spindle 12 adapted to carry upon an

upper-most end thereof by reason of a shoulder 13, a pair of head members 14 and 15 each of which is provided with a pair of oppositely disposed channels 16 and 17 respectively, which channels are adapted to form means for the retention of conventionally shaped portions of standard tool stock such as is, for example, commonly available in $\frac{3}{8}$ " square shape of varying lengths, two pieces of such stock being indicated in the drawing by the numerals 18 and 19 which pieces of tool stock are provided at their outermost ends with suitably shaped knifelike edges 20 and 21 respectively, which edges are tapered as best shown in Figure 2 and which tapers are oppositely formed.

In order that the tools 18 and 19, formed of tool stock, may be held in desirable position in the opposed channels 16 and 17 of the head members 14 and 15, a washer 22 and nut 23 are turned upon a threaded upper-most end 24 of the spindle 12, the nut 23 adapted to exert sufficient pressure upon the heads 14 and 15 to retain the tools 18 and 19 in operative position. This is due primarily to the formation of the channels 16 and 17 which are so formed as to provide a tight fit about the tools 18 and 19.

By referring now to Figure 1 of the drawing, the preferred arrangement of these tools 18 and 19 may be seen as the inner-most ends thereof are shown in dotted lines beneath the head member 14. Still referring to Figure 1, it will be seen that a relatively long striplike section of fiber forming a fiber wedge 25 is positioned horizontally across the opening 11 in the table 10 in a position wherein it is adapted to be engaged by the cutting edges 20 and 21 of the tools 18 and 19 alternately upon the upper and lower surfaces thereof so as to form a beveled edge thereon as illustrated in the drawing. In order to retain the fiber wedge 25 in position and at the same time provide for its being moved endwise so as to progressively bevel the edge of the strip, a spring tensioned clamping piece 26 has been provided which clamping piece 26 is formed with a channel like portion 26A which in turn is adapted to be snugly positioned over a barlike member 27 and movably held thereon by means of a pair of spring tensioned members each of which comprise a spring 28 and a headed shaft 29 which is in turn affixed to the barlike member 27 and passes through an opening in the inverted channel member 26A. The fiber wedge engaging portion 26 is provided with a radius 30 formed therein to facilitate the inspection of the work and its necessary endwise movement as the work progresses.

The barlike member 27 forms a portion of a movable plate 31 which is in turn adjustably positioned on the table 10 by means of bolts 32 engaging slots formed therein.

It will thus be seen that a long strip of fiber may be placed under the clamping piece 26 and thus held in proximity to the arc of the tools 18 and 19 which will upon the rotation of the spindle 12 cause a practical and efficient beveling of the edge of the fiber wedge 25 thus exposed to their action. It will be seen that by moving fiber wedge 25 endwise, the beveling action is continued and that it is thereby possible to bevel an edge of the fiber wedge rapidly and efficiently and that when one edge has been so beveled, the wedge 25 can be removed and reversed so that the other edge may also be beveled. After being beveled the fiber wedge strip is cut to desired lengths. The tools 18 and 19 may obviously be ground by hand or on an emery wheel, no special grinding equipment being necessary, thus assuring lower maintenance cost. As there are no milling cutters used the complete fiber wedge cutting device forms an economical unit and one which may be readily adjusted to creating the same taper on the wedges as the original fibers which are being replaced.

In some generators wooden wedges are used and it is obvious that the device will efficiently form the same. It will be seen that the head members 14 and 15 are extremely simple in forma-

tion and that they can be used either side up when they are assembled. It will be seen that the square cornered channels 16 and 17 formed in the head members 14 and 15 may be easily and accurately formed as they do not depend upon complicated formation or pattern to be effective in adequately holding the cutting tools.

It will also be seen that due to the fact that only one cutting tool engages the work at one time a much smaller motor can be used thus adding to the efficiency and economy of the device.

Having thus described my invention, what I claim is:

15. In a device of the class described comprising a table having an opening formed therein and means adjacent the opening adapted to retain a fiber strip in position adjacent the said opening, a revolvable shaper positioned partially within the said opening, said shaper comprising a pair of head members having oppositely disposed channels formed therein and work engaging tools positioned in the said channels each of the said work engaging tools projecting from opposite sides 20 of the said channels and each of the said work engaging tools beveled in oppositely disposed bevels so that the fiber strip may be engaged alternately upon upper and lower surfaces thereof by the said work engaging tools.
25. In a device of the class described comprising a table having an opening formed therein and means adjacent the opening adapted to retain a fiber strip in position adjacent the said opening, a revolvable shaper positioned partially within the said opening, said shaper comprising a pair of head members having oppositely disposed channels formed therein and work engaging tools positioned in the said channels each of the said work engaging tools projecting from opposite sides 30 of the said channels and each of the said work engaging tools beveled in oppositely disposed bevels so that the fiber strip may be engaged alternately upon upper and lower surfaces thereof by the said work engaging tools.

EARL B. PETERMAN.
